AUTOMATIC LOCK SLIDER

Louis H. Morin and Davis Marinsky, Bronx,
N. Y., assignors to Whitehall Patents Corpora-
tion, Bronx, N. Y., a corporation of New
York

Application May 20, 1938, Serial No. 208,979

8 Claims. (Cl. 24—205)

This invention relates to sliders of separable fasteners and primarily to devices of this kind wherein the body portion or structure of the slider is composed of plastic material, and particularly thermoplastic material, such for example as cellulose acetate, whereby the body portion or parts of the slider may be formed from die castings. More particularly the invention relates to a slider device of the character described having a pawl or latching means normally held in operative position when the slider is at rest and automatically moved into inoperative position to release the slider in the operation of drawing or pulling the slider, by suitable finger piece or pull, in either direction on the fastener stringers. The novel features of the invention will be best understood from the following description and annexed drawing in which certain embodiments of the invention are disclosed and in which the separate parts are designated by suitable reference characters in each of the views, and in which:

Fig. 1 is a plan view of one form of slider which we employ illustrating the arrangement thereof on portions of fastener stringers with part of the structure removed.

Fig. 2 is a longitudinal sectional view through the slider detached.

Fig. 3 is a cross section on the line 3—3 of Fig. 1.

Fig. 4 is a cross section on the line 4—4 of Fig. 2.

Fig. 5 is a diagrammatic perspective view illustrating the arrangement of the pawl or latching member with respect to the pull and eliminating the entire slider body structure.

Fig. 6 is a plan view of the slider body detached.

Fig. 7 is a view similar to Fig. 2 showing a modified form of construction.

Fig. 8 is a section substantially on the line 7—7 of Fig. 6, and

Fig. 9 is a perspective view of the pawl or latching element employed in the structure shown in Figs. 6 and 7 and on an enlarged scale.

In Figs. 1 to 6 inclusive is shown one form of slider construction employing a slider body 10 consisting of top and bottom walls 11 and 12 joined at the wide end of the slider in a conventional V-shaped web 13. The side edges of the walls 11 and 12 have inturned flanges 14 for engaging the links 15, 15a of opposed stringers 16, 16a, note Fig. 1, in the operation of coupling and uncoupling the same in the manner well known in this art.

While in the accompanying drawing we have shown the slider body as well as a finger piece retaining bar 17 as constructed from plastic ma-

terial and particularly die cast thermoplastic material, such for example as cellulose acetate, it will be understood that these parts may be constructed from other materials including metal castings, in which latter event, the parts 10 and 17 may be secured together in other known manners. In forming the parts 10 and 17 of thermoplastic die castings, this process lends itself to the economic formation of the parts, and at the same time contrastive color effects may be produced between the parts 10 and 17 by using different colored materials therein.

The slider body or part 10 is formed with an elongated recess 18 in the outer surface of the top wall 11 at one side of the longitudinal center thereof, one end of the recess 18 opening into a large key recess 19 for receiving a corresponding key member 20 on the part 11. A recess 21 is formed centrally of the other wide end of the slider body 10 to receive a key member 22 on the part 17 in the operation of cementing the part 17 to the part 10.

We provide a pawl, latch or lock unit 23, shown in detail in Fig. 5 of the drawing, and this unit has spaced shaft portions 24, 24a arranged in common alinement. A crank portion 25 has an upwardly arched part 26 having two beveled cam surfaces 27 and 28 at the underside thereof. The crank portion 25 joins the spaced shaft portions 24, 24a, and extending laterally from the shaft portion 24a is a pawl or latching element proper 29 in the form of a downwardly extending hook. The upper surface of said element is recessed as seen at 30 to receive a coil spring 31 which serves to urge the pawl normally in a downward direction or into an operative position.

The recess 18 forms a seat or bearing for the shaft portions 24, 24a. Extending from the recess 18 are hook-shaped recesses 32 for receiving the arms of the crank 25 and part of the crosshead 26 thereof, whereas another recess 33 extends from the recess 18 and opens into an aperture 34 passing through the top wall 11 of the slider. The recess 33 and aperture 34 receives the element 29, the aperture 34 permitting the hook end of the pawl to pass into the channel of the slider to engage the links of one of the stringers, for example the links 15 of the stringer 16, note Fig. 1.

The recesses 18, 32 and 33 serve to normally support the unit 23 in what might be termed a horizontal position with the hook end of the element 29 extending into the channel of the slider, as seen in full lines in Fig. 3 of the drawing. The unit is held in this position by the spring 31. By

pulling upwardly upon the crank 25, the element 29 may be withdrawn from the channel of the slider, as indicated in dotted lines in Fig. 3, to provide free action of the slider on the stringers.

- 5 To permit the movement of the unit 28 above referred to, the bar part 17 is recessed as seen at 35, note Figs. 2 and 4. This recess opens outwardly through one side of the bar as seen at 36 in Fig. 4 so as to encourage upward movement 10 of the crank 25 or the arched crosshead 26 thereof when a finger piece or pull 37 or the crosshead 38 thereof is moved in the direction of either of

sockets or recesses 52 formed in the upper surface of the slider 41. One of these sockets is shown in section in Fig. 8 of the drawing.

It will be noted that sufficient clearance is provided to permit the movement of the unit 23a from the operative position shown in Fig. 8 to a raised or inoperative position to draw the hook-shaped pawl or lock element 53 out of the channel of the slider as will be apparent. The element 53 is arranged at one end of the unit 23a and at one side thereof as will clearly appear in Fig. 11. 5 10

30 species is enough for the detection of either of
many of these bugs or both of the groups

10. By this system we can easily calculate the value of π .

point of reducing the overall dimensions of the entire unit 23.

With both forms of construction, it will appear that in assembling the parts, the pull ring or yoke 37-58 is first arranged upon the upper surface of the slider, after which the unit 23-23a is arranged in position. The spring 31-57 is then placed in position, after which the bar part or member 17-42 is applied and cemented in position. The parts are held in assembled position a sufficient length of time to insure the secure cementing of the parts together.

One of the features of the construction of the device herein shown and described, resides in the fact that movement of the automatically locked slider in either direction is positively prevented except when the slider is made freely movable and operable in either direction on the fastener stringers by drawing upon the finger piece or pull in any direction throughout an arc of 180°, and thereby releasing the locking member. In both forms of construction the lock element or pawl moves in a plane transversely to the longitudinal plane of the slider so that when said element is in locked position, the same forms what may be termed a wedge or perpendicular shoulder which positively stops the feed of the links through the channel of the slider, and this prevents movement of the slider on the stringers. It is here important to note that no pressure upon the pawl or lock element will tend to move the same into inoperative position primarily due to the transverse plane of movement of said element.

Having fully described our invention, what we claim as new and desire to secure by Letters Patent, is:

1. In a lock slider for separable fasteners comprising diverging channels for the passage of fastening elements, an elongated locking member mounted on an outer surface of a wall of the slider and comprising two spaced shaft portions in line with each other and joined by a crank portion, means pivotally supporting said shaft portions on said wall, said shaft portions extending lengthwise of the slider, a latch extending from said locking member and through a hole in the slider into one of said channels to lock the slider, and a handle connected to said crank and arranged to rock said member to lift said latch from locking position.

2. In a lock slider for separable fasteners comprising diverging channels for the passage of fastening elements, an elongated locking member mounted on an outer surface of a wall of the slider and comprising two spaced shaft portions in line with each other and joined by a crank portion, means pivotally supporting said shaft portions on said wall, said shaft portions extending lengthwise of the slider, a latch extending from said locking member and through a hole in the slider into one of said channels to lock the slider, a handle connected to said crank and arranged to rock said member to lift said latch from locking position, and a spring normally urging said latch into locking position.

3. In a lock slider for separable fasteners comprising diverging channels for the passage of fastening elements, an elongated locking member mounted on an outer surface of a wall of the slider and comprising two spaced shaft portions in line with each other and joined by a crank portion, means pivotally supporting said shaft portions on said wall, a latch extending from said locking member and through a hole

in the slider into one of said channels to lock the slider, and a handle connected to said crank and arranged to rock said member to lift said latch from locking position.

4. In a lock slider for separable fasteners comprising diverging channels for the passage of fastening elements, an elongated locking member mounted on an outer surface of a wall of the slider and comprising two spaced shaft portions in line with each other and joined by a crank portion, means pivotally supporting said shaft portions on said wall, a latch extending from said locking member and through a hole in the slider into one of said channels to lock the slider, a handle connected to said crank and arranged to rock said member to lift said latch from locking position, and a spring normally urging said latch into locking position.

5. In a lock slider for separable fasteners comprising diverging channels for the passage of fastening elements, an elongated locking member mounted on an outer surface of a wall of the slider and comprising two spaced shaft portions in line with each other and joined by a crank portion, means pivotally supporting said shaft portions on said wall, a latch extending from said locking member and through a hole in the slider into one of said channels to lock the slider, a cam surface on the under side of said crank portion and inclined towards said wall of the slider, and a handle having a crosshead disposed between said crank portion and said wall and slidable lengthwise of the locking member to engage said cam to lift said latch from locking position.

6. In a lock slider for separable fasteners comprising diverging channels for the passage of fastening elements, an elongated locking member mounted on an outer surface of a wall of the slider and comprising two spaced shaft portions in line with each other and joined by a crank portion, means pivotally supporting said shaft portions on said wall, a latch extending from said locking member and through a hole in the slider into one of said channels to lock the slider, cam surfaces at opposite ends of said crank portion and extending towards said wall, and a handle having a crosshead disposed between said crank portion and said wall of the slider and slidable lengthwise of the locking member so that it may engage either one of said cam surfaces to rock the locking member and to lift said latch from locking position.

7. In a locking slider for separable fasteners comprising a slider body having diverging channels for the passage of fastening elements longitudinally therethrough, a locking member pivotally supported upon one wall of the slider to swing only in a direction perpendicular to the longitudinal axis of said slider and across the path of movement of the fastener elements through the channels thereof, a latch extending from said member into a channel of the slider transversely across the path of movement of the fastening elements through said channels to lock the slider against accidental movement on said elements, means normally urging the latch in locked position, means cooperating with said member to lift the latch from locking position, and a housing arranged upon and keyed and secured to said wall of the slider for concealing the major portion of said member and retaining the same against displacement from the slider.

8. In a lock slider for separable fasteners comprising a channeled body for the passage of fas-

tening elements through the channel thereof, an
elongated hood arranged upon one outer surface
of a wall of the slider centrally and longitudinal-
ly thereof, means keying and securing the hood
5 to the slider wall, a locking member arranged be-
tween the slider wall and said hood and mounted
for free swinging movement only in a direction
perpendicular to the longitudinal axis of said
hood and slider, a latch extending from one side
10 of said member and outwardly through one side

of said hood to enter the channel of said slider
body across the path of movement of the fasten-
ing elements through said channel to lock the
slider, tensional means between the hood and said
member normally urging the latch in locked po-
sition, and means slidably coupled with said hood
and cooperating with said member to lift the
latch from locking position.
